United States Patent

Des. 235,355
Patented June 10, 1975

235,355

MEDALLION

Henry K. Rigg, 18 West St.,
Annapolis, Md. 21404

Filed Nov. 5, 1973, Ser. No. 412,543

Term of patent 3½ years

Int. Cl. D11—02

U.S. Cl. D29—19 R

Fig. 1

Fig. 2

FIG. 1 is a front elevational view of a medallion showing my new design; and

FIG. 2 is a side elevational view thereof.

The rear of the medallion is plain.

I claim:

The ornamental design for a medallion, substantially as shown and described.
